UNITED STATES PATENT OFFICE.

ERNEST S. WILSON, OF GARRISON, IOWA.

ADVERTISING NOVELTY.

1,397,476.

Specification of Letters Patent. Patented Nov. 15, 1921.

Application filed June 11, 1920. Serial No. 383,259.

To all whom it may concern:

Be it known that I, ERNEST S. WILSON, citizen of the United States, residing at Garrison, in the county of Benton and State of Iowa, have invented new and useful Improvements in Advertising Novelties, of which the following is a specification.

This invention relates to advertising devices and aims to combine with a pocket match box, a movable information strip which contains a gestation table, wherein the device will be exceptionally useful to cattle raisers and thereby rendered valuable for advertising purposes.

15 Another object is the provision of a device of this character which is neat and attractive in appearance and of a size to permit of its being easily carried in the pocket of a garment.

20 With the above and other objects in view, the invention further includes the following novel features and details of construction to be hereinafter more fully described, illustrated in the accompanying drawings and 25 pointed out in the appended claim.

In the drawings:—

Figure 1 is an elevation of the device.

Fig. 2 is a transverse section.

Fig. 3 is a section on the line 3—3 of 30 Fig. 2.

Fig. 4 is a similar view on the line 4—4 of Fig. 1.

Referring to the drawings in detail, wherein like characters of reference denote 35 corresponding parts, the invention comprises a casing 10 which is of substantially flat formation and has its opposite side edges rounded. The casing is open at one end and this open end is adapted to be closed by a 40 hinged cover 11 which is provided with a spring cage 12 so that the cover may be held in closed position.

Located within the casing 10 is a transversely disposed partition 14, the latter being 45 slightly spaced from the open end of the casing to provide a transverse compartment 15. Arranged longitudinally within the casing is a tube or central substantially cylindrical compartment 16 which opens at 50 one end into the transverse end compartment 15. Arranged upon each side of the tube or central compartment 16 is a compartment 17 and mounted for rotation in each of these last mentioned compartments is a roller 18. 55 The shafts of these rollers extend through the closed end of the casing and are provided with operating knobs 19.

Secured upon the rollers 18 are the opposite ends of an indicia strip 20, the latter extending through a passage 21 provided 60 between the wall of the intermediate compartment 16 and the adjacent wall of the casing 10. The casing 10 is further provided with a side opening 22, through which the indicia upon the strip 20 will be seen. As 65 previously stated, the device is primarily intended for the use of cattle raisers and for this purpose is provided with a gestation table which includes a number of dates arranged in rows upon the strip, the date to 70 the left of the strip being the date of service, the intermediate date being the date of calving, while the date to the extreme right will be the date of farrowing. Thus, the strip may be moved until the proper date of service 75 appears at the left, whereupon the other two dates will be the date of calving and farrowing. By arranging the interior of the box in the manner shown, matches may be carried therein with their ends projecting 80 into the transverse end compartment 15 so that they will be readily accessible and the usefulness of the device increased.

The invention is susceptible of various changes in its form, proportions and minor 85 details of construction and the right is herein reserved to make such changes as properly fall within the scope of the appended claim.

Having described the invention what is 90 claimed is:—

A device of the class described comprising a casing provided with an elongated opening in one side, having an open end, and a pair of spaced openings in the opposite closed 95 end thereof, a cover hingedly connected to one side of said casing and provided with a spring cage adapted to engage the opposite side and close the open end of said casing, a partition disposed in said casing adjacent 100 said open end and provided with a pair of spaced openings in alignment with the openings in said casing, a tube secured to said partition and arranged longitudinally in said casing, a pair of headed rollers arranged on opposite sides of said tube and extending through the openings in said partition and in said casing, and a pair of operating handles secured to the outer ends of said rollers.

110 In testimony whereof I affix my signature.

ERNEST S. WILSON.
